PROCESS FOR CONVERTING HYDRO-CARBONS

Frederick E. Frey, Bartlesville, Okla., assignor to
 Phillips Petroleum Company, Bartlesville, Okla.,
 a corporation of Delaware

Original application October 6, 1932, Serial No.
 636,555. Divided and this application March 30,
 1936, Serial No. 71,763

15 Claims.

(Cl. 196—10)

This invention relates to an improved process for converting volatile aliphatic hydrocarbons, especially natural gas and/or the gases produced by the cracking and distilling of petroleum, or by the destructive distillation of bituminous materials such as coal, into valuable normally liquid hydrocarbons by thermal treatment. The present application is a division of my application, Serial No. 636,555, filed October 6, 1932, which is now U. S. Patent 2,038,834.

As stated in my parent application, it has been proposed to convert such gases into aromatic oils by heating them to elevated temperatures, 1250-1750° F. for a sufficient time to effect a substantial conversion into aromatic oils. The conversion takes place at atmospheric or higher pressure with the formation of aromatic oils, and, owing to the drastic cracking conditions required, the gaseous hydrocarbons are for the most part destroyed with the exception of methane which is produced in the cracking, and which in itself can be converted into oils by cracking at excessively high temperatures only. Consequently, little material suitable for retreatment is obtained.

It has also been proposed to convert gaseous hydrocarbons into normally liquid hydrocarbons by heating to a reaction temperature under high pressure, above 500 pounds per square inch. In this way gaseous olefines have been shown to polymerize to liquid hydrocarbons in good yield. The conversion of the more refractory gaseous paraffins into normally liquid products has also been proposed. While gases produced by oil cracking processes contain both paraffins and olefines, natural gases contain only the paraffins. At a temperature of preferably 950-1100° F. and pressure of preferably 2000 to 3500 pounds per square inch, butane may be converted in a single cracking operation into normally liquid hydrocarbons mostly aliphatic and alicyclic in nature to the extent of 8-16 per cent. I have found that propane at such pressures requires a higher temperature, while ethane is inferior to propane. In fact, the presence of propane and ethane, I have found, is usually undesirable in admixture with butanes or gaseous olefines to be converted under such high pressures into liquid hydrocarbons, inasmuch as they detract from the efficiency of the conversion unit. In the treatment of the lower boiling paraffins under heat and heavy pressure to produce an optimum conversion into aliphatic and alicyclic hydrocarbons of higher boiling point, I have found that when the time of reaction is the minimum necessary to produce a virtually maximum yield of volatile oils, there sur-

vives a great part of the paraffins treated unaltered, and some of the unchanged paraffins may be advantageously separated from the products and returned to the cracking operation. Methane, 5 ethane, ethylene, propane, and propylene, I have found to be formed in considerable amounts, in such high pressure thermal treatment, that is, in quantities comparable to the oils formed and exceeding 5 per cent of the hydrocarbon treated, 10 and these lower paraffins are not as suitable for retreatment as the butanes. A part of the propane and ethane, however, may be returned with the butane chiefly for the sake of the yield of oils obtainable from the accompanying propylene 15 or ethylene, but a considerable part of the hydrocarbons boiling below butane and butene must be continually discharged from the system. Consequently, in operating to obtain the best economy, a quantity of gas containing propane, ethane, propylene, ethylene, methane and hydrogen is obtained as a by-product.

The conversion of hydrocarbon gases into aromatic oils previously described may be accomplished at moderate pressures, say below 500 25 pounds per square inch, and is applicable to all simple paraffins and olefines, all of which give a substantial yield, of 7 per cent or more, of aromatic oils with the exception of methane which requires prohibitive conversion temperatures.

The present invention deals with a novel 30 method of obtaining liquid products from normally gaseous hydrocarbons, and in accordance with the invention I propose to scrub olefine-containing gases with liquid butane and thereby concentrate the olefine content thereof. Subsequently the concentrated olefine gases are converted at elevated temperatures to obtain a yield of liquid products.

With the foregoing object outlined and with 40 other objects in view, the invention consists in the novel features hereinafter described in detail in connection with the accompanying drawing, which shows an elevation of an apparatus suitable for the practice of my invention.

45 A charging stock consisting predominantly of butane but which may contain gaseous olefines and limited amounts of lower paraffins is delivered by pumps 1, 2 and 3 continuously under a pressure between 500 pounds and 5000 pounds 50 per square inch through a heating tube 4 positioned within a furnace housing 5 wherein the hydrocarbons are maintained at a conversion temperature preferably between 750° and 1200° F., for a time sufficient to effect the conversion 55 of a substantial portion of the charging stock

into normally liquid hydrocarbons, together with quantities of paraffins and olefines lower than butane and butene. The thermally treated hydrocarbons are discharged into a primary condenser 6 maintained under substantially the same pressure as the coil 4, where the temperature is reduced by direct or indirect cooling means to effect condensation of some gasoline and heavier liquid hydrocarbons. The liquid is separated in separator 7 from vapors, and the vapors are discharged into a secondary cooler condenser 8 and a separator 9. A further extraction of heat takes place in condenser 8 and the greater part of the uncracked butane, together with the remainder of the normally liquid hydrocarbons are condensed. Vapors discharged from 9 enter an absorber or rectifier 10, still under such high pressure, and therein undergo further condensation and come into contact with an absorption liquid which, under the conditions existing in the absorber, absorbs ethane, ethylene, and higher hydrocarbons, leaving in the unabsorbed gas the greater part of the methane and any gases of lower boiling point, which gases are discharged from the absorber through a pipe 10a that leads to the lower portion of a heat exchanger 11 of the plate and tube type. After passing through the tubes of the heat exchanger, these gases are discharged through a pipe 11a and some of the same may be expanded through an expansion valve 11b and a conduit 11c back into the heat exchanger 11. Due to the expansion of this portion of the gases, a very low temperature will be maintained in the heat exchanger and this will result in the condensation of a portion of the gases entering the heat exchanger from the pipe 10a. Such condensate is returned to the top of the absorber or rectifier through a pipe 10b. Gas which has been expanded through the heat exchanger may be vented from the system through the pipe 11d.

If desired, some of this high pressure gas may be also utilized as a cooling agent for other purposes. For example, some of the gas from pipe 11a may be fed through a manually controlled valve 11e, pipes 11f and 11g and an expansion valve 11h to any suitable point in the system where a refrigerating effect is desired.

Should it be desired to crack this gas which is high in methane, some of it may be fed from the pipe 11f through pipes 11i and 11k into a low pressure cracking unit 14.

If preferred, some of the gas which is high in methane may be vented from the system through the line 13 by passing the same through a valved pipe 13a which connects pipes 11f and 13.

By reason of the high pressure existing in a portion of the system, liquefied hydrocarbon gas, preferably butane, may be used as an absorption or reflux medium in 10. This medium extracts the valuable hydrocarbons more effectively at a reduced temperature. Accordingly, butane from a pipe 13b is mixed with the cold condensate from the heat exchanger 11 before said condensate enters the absorber or rectifier.

The liquid separated in 10 contains the absorption medium, the butane and butene not previously condensed, and the greater part of the propane, propylene, ethane and ethylene formed by the high pressure conversion operation. This liquid is discharged by pipe 15 through a pressure regulator 15a into a rectifier and condenser 16 and 17 in which the butane and butene mixed

with a controlled limited proportion of propane and lighter hydrocarbons are separated under a pressure of about 500 pounds per square inch, and returned by pump 3 through pipe 18 to be retreated in the high pressure conversion coil 4. Hydrocarbons lighter than butane, in gaseous and liquid condition, pass respectively from condenser 17, through pipes 17b and 17c to an exhausting or rectifying column 19 in which lighter hydrocarbons, chiefly methane may be separated under a pressure of about 500 pounds per square inch and discharged through pipe 20, leaving the system at 13. The liquefied hydrocarbons discharged at 22 are chiefly ethane and ethylene, propane and propylene, and are led through a pressure reducing valve 22a to the low pressure cracking unit 14 for conversion into aromatic oils under a pressure between atmospheric and 500 pounds per square inch, but preferably about 150 pounds per square inch. If the quantity of methane is not large, it need not be separated and discarded, and by opening valve 23, all the vapors from 17 may pass directly to the cracking unit 14.

The normally liquid hydrocarbons formed in the high pressure conversion coil 4 which condense, together with the butane, in 8 and 9, are fractionated in a rectifier 24 having a still 25; the butane and lighter hydrocarbons being delivered by pump 26 through pipes 26a and 15 into the rectifier 16 wherein butane and butene are separated and passed through 16a, 3 and 16b, ultimately into pipe 18 to return to the high pressure conversion coil, while lighter vapors may be allowed to pass through a pressure regulator 31 and into the cracking unit 14. The normally liquid hydrocarbons are fractionated in the rectifier 27 together with the condensate from 7, which enters through pipe 29, and the vapors from the rectifier 27 are condensed in a condenser 27a and such condensate becomes the motor fuel distillate which is collected in a receiver 30. A less volatile residue is discharged from the still 28.

45 A conventional reflux condenser 27b is positioned between the rectifier 27 and condenser 27a.

Normally liquid hydrocarbons, as for example, the higher boiling fractions of natural gasoline, of low anti-knock value, may be introduced, preferably mixed with other charging stock, to the high pressure conversion coil 4 at 32 to undergo conversion into liquid hydrocarbons of higher anti-knock value, which are recovered at 30. Or such material, as well as gases of high olefine content, may be charged into an intermediate point of the high pressure conversion zone at a point 33 nearer the exit to avoid excessive reaction in case a refractory charging stock requiring a high temperature, such as butane, is at the same time undergoing treatment and entering from pipe 18.

The gaseous hydrocarbons lighter than butane, produced by the pressure conversion operation and separated as described, are passed into a common conduit 35 into which also may be led other hydrocarbon gases of limited methane content, which may be available at a moderate pressure. These gases pass into the low pressure cracking unit 14 in which they are heated to a temperature of 1250-1750° F., for a time sufficient to produce a substantial yield of aromatic oils. The reaction products are discharged from 14 through a conduit 14a into a primary cooler 36 in which by either direct or indirect cooling

means, the temperature is reduced and tar separated; thence into an extraction plant 37 in which the remainder of the oils, which are largely aromatic, are separated and a small amount of lighter olefinic hydrocarbons may be isolated and returned to either conversion zone through valved pipes 38 or 40. The dry gas is then discharged from the system through pipes 38 and 43. The gases discharged from the system, owing to their high hydrogen-carbon ratio, are particularly suitable for the production of hydrogen.

Since methane is the only gaseous hydrocarbon unsuitable for conversion into aromatic oils, all available hydrocarbon gases except those containing excessive amounts of methane may be treated in the low pressure cracking unit 14 to produce aromatic oils, including gases predominating in butane and butene, which, while suitable for conversion in higher yields into oils by high pressure conversion, may be available in excessive quantities or under pressures so low as to unfit them for conversion in the high pressure unit 4. For the high pressure conversion operation, hydrocarbons higher than propane are most suitable, but when propylene or ethylene are present in substantial concentrations in lighter gases, they are suitable for conversion in the high pressure unit, whether or not a high concentration of butane accompanies them. The operating conditions giving best results depends on the composition of charging stock. The conversion of butanes containing olefines in small amounts may be conducted at 1000-5000 pounds per square inch pressure, and 950-1200° F., the higher temperatures within the range being the more effective if ethane and propane are present in substantial amount. Lower temperatures are preferable when a high olefine content accompanies the paraffins, temperatures as low as 750° F. and pressures as low as 500 pounds per square inch giving good results when olefines predominate in the charging stock. A particularly suitable charging stock is the more easily liquefied gases produced in cracking petroleum, which gases predominate in butanes and butenes. Such gases may be converted to the extent of 50% and even more, into normally liquid hydrocarbons, while butanes give a somewhat lower yield, even with the greater extent of recycling which they require.

Gases from various sources, subject to the above limitations, may be treated in the high pressure and the low pressure conversion operations while retaining the advantages of the novel combination of this invention. By the use of extraction by means of oil absorption, followed by distillation, concentrates of suitable gases may be obtained in liquid form and under high pressure without the use of costly direct compression, and in some cases direct compression with or without the use of a liquid pump for further increasing the pressure may be profitably employed.

In conjunction with a natural gasoline extraction plant or a refinery, additional economies can be effected. The products of the high pressure conversion operation conducted in coil 4, can be cooled in heat exchange relation with oils and gases of lower temperature, thereby effecting heat economies, and the products of the low pressure cracking step, formed at a higher temperature, may be used to effect cracking as well, both in contact and out of contact with oil to be cracked. Condensing and distilling units may likewise be used to perform a dual

role in effecting separations of hydrocarbon constituents in connection with both the process for gas conversion and refinery gasoline plant operations, and many other obvious advantages can be gained from such combination.

Both the high pressure and low pressure conversion operations yield a substantial amount of normally liquid hydrocarbons when, in accordance with the foregoing disclosure, the appropriate hydrocarbons are heated to the proper temperature for a time sufficient to effect the desired conversion. Heat may be introduced continuously throughout the reaction periods or introduced chiefly during the first part of either reaction step without affecting the composition of the products from either conversion operation to such a degree that the combination process is inapplicable. The low pressure conversion is preferably conducted in accordance with U. S. Patent 1,847,238, March 1, 1932, and the high pressure conversion may be conducted in either one or two stages.

As an example of the process, a mixture of the butanes containing 70% n-butane and 30% iso-butane was converted at 975° F. and 3100 pound pressure for a period of approximately 10 minutes, then maintained for a shorter time at a somewhat lower temperature to further synthetic reactions. Carbon formation was slight. 40% of the butane was discharged unconverted accompanied by 4% by weight of heavy oils, and 15% of normally liquid hydrocarbons boiling between 30 and 225° C. having a specific gravity of .725 at 20° C. The remainder consisted of gaseous products. The analysis of the gases in volume per cent was as follows:

	Volume per cent
Hydrogen	1.0
Methane	40.5
Ethane	16.8
Ethylene	2
Propane	11.1
Propylene	1.3
Butanes	27.7
Butylenes	1.6
Total	100.0

Owing to the low olefine content, the gases lighter than butane and butene would decrease the throughput of the plant when added to the butane, which is recycled. The gaseous products of the above composition, exclusive of butane and butene, may be cracked at 1475° F. with an exposure time of 0.2 minute to produce 0.7 gallon of benzol per thousand cubic feet or, when the methane is separated and ethane, ethylene, propane, and propylene are cracked, 1.6 gallons per thousand cubic feet. In the complete conversion of this butane mixture by the combination process in which all unconverted butane and butene formed are returned to the pressure conversion, a yield of about 30 per cent by weight of gasoline is obtained, together with 7 per cent by weight of benzene. Heavy oil and tar amounting to about 7 and 4 per cent respectively, are formed. About 52 per cent of the original hydrocarbon survives the conversion steps as a gas suitable for fuel, containing chiefly, methane, but the gas produced by high temperature cracking contains about 16 per cent of ethylene and 4 per cent propylene and butylene by volume, which may be extracted under favorable conditions for treatment in either conversion step. The yields of normally liquid hydrocarbons will be aug-

mented when gases containing olefines are available for treatment.

It will be noted that the combination is flexible in that the relative proportions of products from the high pressure and low pressure process can be varied within certain limits, and thereby render the combination process capable of operation under the most advantageous conditions. In other words, the yield of benzol from the low pressure cracking unit 14 could be increased at the expense of a decrease in yield of liquid products from the high pressure conversion zone 4. This mode of operation could be followed when the market price of benzol was considerably higher than the market price of high octane motor fuel.

While I have disclosed preferred ways of practicing the process, it will be understood by those skilled in the art that changes in procedure may be resorted to without departing from the spirit of the invention, as set forth in the claims.

What I claim and desire to secure by Letters Patent is:

1. In a process of the character described, scrubbing hydrocarbon gases including olefinic gases while under superatmospheric pressure with a liquid menstruum composed principally of hydrocarbons of three and four carbon atoms per molecule and thereby concentrating the olefinic gases, releasing the pressure on undissolved gases to permit the undissolved gases to expand and absorb heat, utilizing the cold thus created to cool the menstruum before contacting the menstruum with the first-mentioned hydrocarbon gases, discharging the expanded undissolved gases from the process, separating said concentrated olefinic gases from the menstruum, and subsequently converting the last-mentioned concentrated olefinic gases at elevated temperatures and thereby obtaining liquid products.

2. In a process of the character described, scrubbing hydrocarbon gases including olefinic gases while under superatmospheric pressure with a liquid menstruum composed principally of hydrocarbons of three and four carbon atoms per molecule and thereby concentrating the olefinic gases, releasing the pressure on undissolved gases to permit the undissolved gases to expand and absorb heat, utilizing the cold thus created to cool the menstruum before contacting the menstruum with the first-mentioned hydrocarbon gases, discharging the expanded undissolved gases from the process, separating said concentrated olefinic gases from the menstruum, and subsequently converting the last-mentioned concentrated olefinic gases at elevated temperatures between 1250° F. and 1750° F. and thereby obtaining liquid products.

3. In a process for the conversion of normally gaseous hydrocarbons into normally liquid hydrocarbons, scrubbing a gaseous mixture containing butane, butene, propane, propylene, ethane, ethylene, methane and hydrogen, with a liquid menstruum composed principally of hydrocarbons of three and four carbon atoms per molecule and thereby separating the butanes, butenes, propane, propylene, ethane and ethylene from undissolved methane and hydrogen, discharging the undissolved methane and hydrogen from the process, and then converting the butanes, butenes, propane, propylene, ethane and ethylene at elevated temperatures to produce liquid oils.

4. In the process for the conversion of normally gaseous hydrocarbons, the steps which comprise scrubbing a gaseous mixture comprising C₃

to C₄ hydrocarbons along with methane while under an elevated superatmospheric pressure with a liquid menstruum composed principally of hydrocarbons heavier than C₃ hydrocarbons to separate C₃ and heavier hydrocarbons from undissolved lighter gases, releasing the pressure on said undissolved lighter gases to permit the undissolved gases to expand and absorb heat, utilizing the cold thus created to cool the menstruum before contacting the menstruum with the first mentioned gaseous mixture, discharging the expanded undissolved gases from the process, separating the absorbed gases from the menstruum, and subsequently converting the last mentioned gases at elevated temperatures and thereby producing liquid hydrocarbons.

5. The process of claim 4 wherein the liquid menstruum comprises principally butane.

6. A process for the conversion of normally gaseous hydrocarbons, which comprises scrubbing predominantly hydrocarbon gases including olefinic gases and gases lower boiling than C₃ hydrocarbons while under an elevated superatmospheric pressure with a liquid menstruum composed principally of butane to concentrate the olefinic gases, releasing the pressure on undissolved gases to expand them and absorb heat, utilizing the cold thus created to cool the menstruum before contacting the menstruum with the first mentioned gases, discharging the expanded undissolved gases from the process, separating said concentrated olefinic gases from the menstruum, and subsequently converting the last mentioned concentrated olefinic gases at elevated temperatures and thereby producing liquid hydrocarbons.

7. A process for the conversion of normally gaseous hydrocarbons, which comprises scrubbing predominantly hydrocarbon gases including olefinic gases and gases lower boiling than C₃ hydrocarbons while under an elevated superatmospheric pressure with a liquid menstruum comprising substantially entirely normally gaseous hydrocarbons, mainly butane to concentrate the olefinic gases, releasing the pressure on undissolved gases to expand them and absorb heat, utilizing the cold thus created to cool the menstruum before contacting the menstruum with the first-mentioned gases, discharging the expanded undissolved gases from the process, and subjecting a hydrocarbon mixture comprising said concentrated olefinic gases to conversion to produce hydrocarbon liquids.

8. The process of claim 7 wherein the said hydrocarbon mixture converted also comprises at least a part of the butane of said liquid menstruum.

9. A process for the production of normally liquid hydrocarbons in the motor fuel boiling range from lower boiling hydrocarbons, which comprises scrubbing predominantly hydrocarbon gases including olefinic gases and gases lower boiling than C₃ hydrocarbons while under an elevated superatmospheric pressure with a liquid menstruum comprising substantially entirely normally gaseous hydrocarbons, mainly butane to concentrate the olefinic gases, releasing the pressure on undissolved gases to expand them and absorb heat, utilizing the cold thus produced to cool the menstruum before contacting the menstruum with the first-mentioned gases, discharging the expanded undissolved gases from the process, and subjecting a hydrocarbon mixture comprising said concentrated olefinic gases together with at least a part of the butane of said

liquid menstruum to a conversion under a pressure in excess of 500 pounds per square inch at a temperature and for a period of time to produce liquid hydrocarbons in the motor fuel boiling range.

10. A process for converting hydrocarbons consisting largely of butanes into higher boiling hydrocarbons, which comprises subjecting the first-mentioned hydrocarbons to conversion in a heating zone at temperatures of 750 to 1200° F. and pressure of 500 to 5000 pounds per square inch, separating the effluent from said heating zone into a gasoline and heavier fraction and a lighter fraction, scrubbing said lighter fraction with a liquid menstruum composed principally of butane, eliminating undissolved gases from the system, separating absorbed C₂ and C₃ hydrocarbons from the menstruum and converting said C₂ and C₃ hydrocarbons at temperatures between 1250 and 1750° F. and under a pressure between atmospheric and 500 pounds per square inch for a sufficient period of time to produce a substantial yield of aromatic oils and subsequently recovering said aromatic oils.

11. In a process for obtaining liquid products from dilute olefinic gases, the steps of concentrating said dilute olefinic gases by scrubbing with a liquid butane menstruum, eliminating undissolved gases from the system, and subjecting concentrated olefinic gases together with at least a part of the butane of said liquid menstruum to a conversion under a pressure in excess of 500 pounds per square inch at a temperature and for a period of time to produce liquid hydrocarbons in the motor fuel boiling range.

12. In a process for obtaining liquid products from dilute olefinic gases, the steps of concentrating said dilute olefinic gases by scrubbing with a liquid butane menstruum, eliminating undissolved gases from the system, separating absorbed C₂ and C₃ hydrocarbons from the menstruum and converting said C₂ and C₃ hydrocarbons at temperatures between 1250 and 1750° F. and under a pressure less than 500 pounds per square inch for a sufficient time to produce a substantial yield of aromatic oils, subsequently recovering said aromatic oils, subjecting a hydrocarbon mixture comprising heavier concentrated olefinic gases together with at least a part of the butane of said liquid menstruum to a conversion under a pressure in excess of 500 pounds per square inch at a temperature and for a period of time to produce liquid hydrocarbons in the motor

fuel boiling range, and subsequently recovering said liquid hydrocarbons.

13. In a process for obtaining liquid products from gaseous hydrocarbons, the steps which comprise scrubbing gases predominantly hydrocarbon and including olefinic gases and gases lower boiling than C₂ hydrocarbons while under an elevated superatmospheric pressure with a liquid menstruum composed principally of butane to concentrate the olefinic gases, discharging undissolved gases comprising gases lower boiling than C₂ hydrocarbons from the process, and subjecting a hydrocarbon mixture comprising said concentrated olefinic gases together with at least a part of the butane of said liquid menstruum to a conversion under a pressure in excess of 500 pounds per square inch at a temperature and for a period of time to produce liquid hydrocarbons in the motor fuel boiling range, and subsequently recovering liquid hydrocarbons in the motor fuel boiling range so produced.

14. A process for separating normally gaseous hydrocarbon mixtures which comprises subjecting the mixture to reflux fractionation, subjecting the separated overhead gaseous light fractional product of the fractionation to cooling and partial condensation under a substantial superatmospheric pressure, separating the condensate from the uncondensed gas, releasing the pressure on such uncondensed gas to further cool it, utilizing such cooled uncondensed gas as a cooling medium in the specified cooling and partial condensing step, and utilizing said separated condensate as reflux in the specified fractionation operation.

15. A process for fractionating mixtures of normally gaseous hydrocarbons which comprises introducing the mixture to be fractionated into a fractionating zone, therein separating said mixture into an overhead vaporous fraction and a liquid residue, withdrawing said vaporous and said residual fractions from said zone, flowing said vaporous fraction while under a substantial superatmospheric pressure in indirect heat exchange relation with a cold expanded hydrocarbon gas to partially condense said overhead fraction, separating the vaporous portion thereof from the liquid portion, returning said liquid portion to said fractionating zone as reflux, reducing the pressure on said vaporous portion to expand and cool the same, and utilizing the thus cooled vapors as the cold expanded hydrocarbon gas in the heat exchange step specified.

FREDERICK E. FREY.
